UNITED STATES PATENT OFFICE

LELAND W. HUNTINGTON, OF OAKLAND, CALIFORNIA

DESIGN FOR AN INVALID TABLE

Application filed November 11, 1929. Serial No. 33,400. Term of patent 3½ years.

To all whom it may concern:

Be it known that I, LELAND W. HUNTINGTON, a citizen of the United States, residing at Oakland, county of Alameda, State of California, have invented a new, original, and ornamental Design for Invalid Table, of which the following is a specification, reference being had to the accompanying drawings, forming part thereof.

The figure is a perspective view of the invalid table, showing my new design.

I claim:

The ornamental design for an invalid table substantially as shown.

LELAND W. HUNTINGTON.
